UNITED STATES PATENT OFFICE.

FRED H. GOOSMANN, OF CINCINNATI, OHIO.

CENTRIFUGAL PUMP.

1,410,564.

Specification of Letters Patent. Patented Mar. 28, 1922.

Application filed March 20, 1920. Serial No. 367,518.

To all whom it may concern:

Be it known that I, FRED H. GOOSMANN, a citizen of the United States, and residing at Cincinnati, in the county of Hamilton and State of Ohio, have invented a new and useful Improvement in Centrifugal Pumps, of which the following specification is a full disclosure.

My invention relates to a centrifugal liquid pumping apparatus, primarily adapted for supplying a liquid coolant to the cutting tools of machine tools, elevating the coolant from a reservoir at the base of the machine and delivering it in a heavy, uniform, non-splashing flow to the tool. The coolant after being delivered for redelivery, carrying with it cuttings and grit or sediment, which in degrees are taken up by the pump, varying according to the capacity of the reservoir or a long, continuous pumping period, which does not give the sediment time to settle in the reservoir, and unless passed unobstructedly through the pump, will collect to clog the pump. Water, in a large percentage, is the base of the coolant generally used, although it is sometimes desirable to use a heavy or viscous cutting oil or lubricant. Therefore, the pump must be adapted to serve efficiently with different kinds of fluids.

The pump usually being in driven connection with the machine, is started and stopped with the control of the machine it is essential that the pump does not lose its prime during each idle interval or rest period.

To fulfil the foregoing requirements, my invention contemplates and has for its objects a centrifugal pump, simple and substantial in construction, with few members or working parts, efficient in operation and which may be manufactured at a small expense.

A device eliminating the use of valves and fine mesh strainers, as any foreign substance entering the intake opening will pass through the pump and not clog the impeller.

A suction intake and discharge outlet at relatively different elevations and both above the priming well, transmitting a constant prime when stopping or reversing the motion of the impeller. The impeller has ample clearance, and in its conjunction with a large horizontal volute, clogging is entirely prevented.

An impeller sustained as a floating member free from the walls of the pump casing.

No bearing inside of the pump body to be ruined by the grit in the coolant.

The driving mechanism as a unit mounted upon the pump body and adjustable in a similar capacity for various installation requirements.

The drive gears are entirely separated from the impeller casing and are enclosed in an oil bath providing splash lubrication for the said gears.

My pump is composed essentially of four castings, two drive shafts, two intermeshing gears and the necessary fastening and packing elements.

Following is a description, in detail, of the construction and operation of my apparatus, like numerals referring to corresponding parts throughout the drawings hereunto annexed, said drawings forming a part of my specification, in which:

Figure 1 is a general perspective view of my liquid pumping apparatus.

Figure 2 is a vertical sectional view of the same, taken centrally through the suction intake, impeller and gear casings.

Figure 3 is a top plan view of my liquid pumping apparatus.

Figure 4 is a side elevation of the impeller and a portion of its shaft.

Figure 5 is a top plan view of the impeller.

Figure 6 is a bottom plan view of the same.

Figure 7 is a horizontal sectional view of the impeller casing, and of the volute and discharge opening, taken on line 7—7, Fig. 2.

Figure 8 is a bottom plan view of the removable top gear casing.

Figure 9 is a top plan view of the oil reservoir and gear casing, showing in dot and dash lines the position of the right angle spiral drive gear, its shaft and pulley.

Figure 10 is a fragmentary bottom plan of the oil reservoir and gear casing, showing the arrangement of the depending lip surrounding the intake opening at one of its sides.

Figures 11 and 12 are diagrammatic plan views showing the manner in which the gear casings may be angularly adjusted at angles of 45°, or multiples thereof, to meet any conditions of use.

Referring to the drawings, 1 designates the pump casing or body of cylindrical form,

provided with a substantially spherical bottom portion 2. The body interiorly and at its intermediate portion has a horizontal volute or convolute channel 4 terminating 5 to a tangent discharge opening 5 co-extensive and horizontally aligned with the volute 4, the same being interiorly threaded at 6 for the connection of suitable discharge pipe 7, see Figs. 11 and 12. The cylindrical 10 casing or body 1 has an open upper end bored and faced to receive the closure member 8 as a part of the impeller and transmission casing secured by screws 9 to the casing 1.

15 Within the casing 1 is placed an impeller 10 of cast construction, having spiral vertical blades 11 depending or extending from a horizontal annular ring portion 12, integral with the said spiral blades, and a 20 central shaft receiving socket 13 connecting with the inner edges of the blades for the reception of the vertical impeller shaft 14.

A gear casing and oil reservoir is shown 25 as of two-part construction, one part 15 is substantially of rectangular form, having side walls 16, a curved end wall 17, and the opposite end wall is formed with a suction intake opening and passage 18, communicating with the impeller casing 1, and delivering the liquid supply downwardly to the impeller 10, through the opening 12', of the ring portion 12, of the said impeller. The lower portion of the casing is provided with a disk-like flange 8, drilled to receive 30 the screws 9, the screws engaging openings 9' of the impeller casing 1.

Thus the flange provides a closure for the impeller casing and may be swivelled for 40 angular adjustment of the gear casing with respect to the impeller casing for changing the angle and location of the pulley to meet the various installation requirements and to make a convenient driving connection.

The said casing 15 is further provided 45 with semi-circular, horizontal, shaft-receiving bearings 19, for the reception of a shaft 20, the said shaft being provided with a drive pulley 21, or with a drive gear, (not shown).

50 The shaft 20 is also provided at its mid-portion with a rigidly-attached, right-angled, spiral gear 22 in mesh with a smaller, similar gear 23 keyed to the impeller shaft 14. Shaft 14, below the gear 23, is mounted 55 for rotation in a bush-bearing and stuffing-box gland 25. The upper end 26, of the shaft 14, is machined to a reduced diameter to receive the gear 23 and provide a shoulder 27 against which the gear rests. The gland 60 and bearing sleeve 25 sockets into a stuffing-box bore formed in the hub portion 25', of the casing 15, to provide a seal against the fluid from the impeller chamber escaping into the transmission casing, and also to 65 prevent the oil in the gear casings escaping

into the pump chamber. The shaft and stuffing-box, located above the pump chamber and extending in a vertical plane, is an additional precautionary measure against fluid leakage into the transmission chamber. 70 A spacing thimble or journal-bush 26' surrounds the reduced extension 26, of the impeller shaft 14, its lower end rests upon the gear 23 and projects through the bearing bore in the cover casing 34, the upper 75 end of the thimble engages the lower surface of a hanger-disk or washer 29. Said hanger-disk 29, a similar disk 30, nut 31 and the upper surface 32, of the cast and bored portion 33, of the upper cover 34, 80 coact to form an adjustable suspending means for the impeller shaft 14 and its connected parts. It will be apparent that slight vertical adjustments of the said shaft 14 may be readily made. 85

The upper cover 34, in addition to the cast and bored portion 33, is provided with a hollow arcuate portion 35, the purpose of which is to receive and enclose the gear 22 and to form an oil case for said gear. 90

The cover 34 is further provided with semi-circular, horizontal, shaft-receiving bearings 36, which bearings coact with the bearings 19 to receive the shaft 20.

The cover 34 is also provided with centering pins 37, which engage the openings 38, of the gear casing and oil reservoir 15, to enable the cover 34 to be easily adjusted to position. When the cover has been so adjusted, clamping screws 39 are applied to 100 firmly secure the same. The cover 34, at opposite sides of the hub bearing for the shaft 14, is provided with openings 40, aligned over the fastening screw of the gland 25, rendering access to the screw with 105 a screw driver inserted through said opening, for tightening the gland when occasion requires.

In the operation of my liquid pumping apparatus, suitable power is applied to the 110 pulley 21, and through shaft 20, gears 22, 23, and shaft 14, rotary motion is imparted to the impeller 10. The liquid to be pumped enters at the intake 18, and is delivered downwardly through the opening 12', of ring 12, of impeller 10, to spiral blades 11, the said blades discharging the liquid 115 through the discharge opening 5.

The impeller casing represents a bowl-like structure providing a lower well or basin portion for holding a priming charge of liquid, with the wall of the casing interiorly above the well portion annularly recessed to form a volute channel developing into a discharge port or passage having its axis in 120 a line tangent to the inner circumferential surface of the casing. 125

The inlet passage is located at a higher elevation than the outlet passage, and, therefore, both the inlet and outlet are disposed 130

at an elevation non-draining to the well, so that a priming charge is constantly maintained in the well and cannot be discharged by any reverse impeller rotation. This is quite a factor when the pump is used for supplying a coolant to the cutting tool of a machine tool, as the pump can be installed in positive driving connection with the driving mechanism for rotating or feeding the work or cutting tool, as the case may be, of the machine tool, without the interposition of the clutch mechanism for pump control upon each reverse of the driving mechanism of the machine tool. The pump is always ready for duty to supply the coolant when the impeller is rotated in the appropriate pumping direction and does not discharge the prime through the suction opening when the impeller rotation is reversed.

The base flange 8 of the transmission casing, which also provides a cover for the pump body at the inlet port 18, is provided with a segmental flange 50 extending around a portion of said port, providing a guard or baffle, at the mouth of the inlet passage, to break the whirling velocity of the liquid within the pump upon the reverse rotation of the impeller and thereby prevent any rising or elevating tendency of the liquid upwardly through the inlet passage, which would expel the priming charge of liquid from the well; the flange deflecting the liquid downwardly into the well, trapping the same discharge through the inlet passage.

The impeller depends into the well or basin, and its blades are free from contact with the wall of the casing, insuring a full pumping efficiency regardless of chips or dirt that may be present in the coolant. The space between the wall of the casing and the blades of the impeller provide a sufficient clearance to prevent the chips or dirt clogging between the impeller blades and the casing wall, therefore the impeller is suspended within the casing as a free floating member, having no rubbing or bearing contact with any part of the pump body, which may impede the rotation of the impeller or cause any wear between the parts.

The transmission mechanism for the impeller is housed within its own casing, which provides a closure cap for the well and impeller shaft, extending in a vertical plane through a stuffing-box in the cap or base portion of the transmission casing, preventing leakage between the well and transmission casing. Thus the oil in the transmission casing is confined in the casing and no grit or liquid can be conveyed from the impeller web into the transmission casings. With the impeller shaft having its bearing in the transmission casing above the pump body, the number of openings into the pump body are reduced, and, therefore, reducing

the opportunities for leakage, and enabling the impeller web to be more securely sealed for increased pump efficiency.

The whole structure is very simple and durable with the parts requiring adjustment easily accessible without dismantling the pump.

Having described my invention, I claim:

1. In a liquid pumping apparatus, the combination of a casing, a vertically suspended impeller within said casing, constructed with vertical, spirally-arranged blades rigidly attached to a horizontal annulus, the said impeller being disposed in operative relation to a horizontally arranged channel of volute form recessed in the interior of said casing, and means for rotating said impeller.

2. In a liquid pumping apparatus, the combination of a casing, a vertically suspended impeller within said casing, said casing having a horizontal channel of volute form arranged in operative relation to said impeller, an inlet opening arranged above the impeller, a discharge opening arranged below said inlet opening, and co-extensive with said horizontal channel, means for rotating said impeller, and provision for changing the angularity of the rotating means.

3. In a pumping apparatus, a pump casing of bowl-like structure, having a volute channel recessed within its upper, inner surface, a closure member for said casing, a shaft engaged through said closure member and projecting into said pump casing, and an impeller fixed upon said shaft and depending into said casing.

4. In a pumping apparatus, a pump casing, an impeller within the casing, a transmission casing secured to and providing a closure for the pump casing, and a shaft journaled within said transmission casing and extending into the pump casing for dependingly supporting said impeller mounted thereon, and transmission means with said transmission casing for rotating said shaft.

5. In a pumping apparatus, a pump casing of bowl-like structure, having a volute channel recessed within its upper, inner surface, and providing a well below said channels for holding a priming charge of liquid, a closure member for said casing, and an impeller rotatably suspended from said closure member and dependingly into said casing.

6. In a pumping apparatus, a pump casing of bowl-like structure, providing a well for receiving an impeller and for holding a priming charge of liquid and having a discharge port at an elevation above the well portion, a closure member for said casing, and an impeller rotatably suspended from said closure member and dependingly into the well portion of said casing.

7. In a pumping apparatus, a pump casing of bowl-like structure, providing a well for receiving an impeller and for holding a priming charge of liquid and having a discharge port at an elevation above the well portion, a closure member for said casing, an impeller rotatably suspended from said closure member and dependingly into the well portion of said casing, said impeller being substantially free from contact with the wall of said casing.
8. In a pumping apparatus, a pump casing of bowl-like structure, a closure member for said casing, and an impeller rotatably suspended from said closure member and dependingly into the casing substantially free from contact with the wall of the casing.
9. In a pumping apparatus, a pump casing of bowl-like structure, a closure member for said casing, and an impeller rotatably suspended from said closure member and dependingly into the casing substantially free from contact with the wall of the casing, said impeller comprising an annulus, having a series of spiral blades projecting from one side of said annulus, the blades joined by a hub element concentric with said annulus.
10. In a pumping apparatus, a pump casing of bowl-like structure, having a volute channel recessed within its inner surface and terminating into a discharge passage,

having an axis tangent to the inner surface of the casing, a closure member for said casing, having an inlet passage leading into said casing, an impeller rotatably suspended from said closure member and dependingly into said casing.

11. In a pumping apparatus, a pump casing of bowl-like structure, having a suitable discharge outlet and impeller rotatably suspended within said casing, a closure member for said casing, having an inlet passage leading into said casing, a segmental baffle surrounding a portion of the end of said inlet passage within said chamber to prevent the impeller forcing liquid from said chamber through said inlet passage during the reverse impeller rotation.

12. In a pumping apparatus, an open top pump casing, a transmission casing, providing a closure for said pump casing and secure thereon to adjustable position, an impeller rotatably suspended from said transmission casing dependingly into said pump casing, and transmission means within said transmission casing for rotating said impeller.

In witness whereof, I hereunto subscribe my name, as attested by the two subscribing witnesses.

FRED H. GOOSMANN.
